No. 898,035.

PATENTED SEPT. 8, 1908.

C. L. BUCKWALTER.

AUDIPHONE.

APPLICATION FILED FEB. 13, 1908.

UNITED STATES PATENT OFFICE.

CYRUS L. BUCKWALTER, OF LOUDONVILLE, OHIO.

AUDIPHONE.

No. 898,035.

Specification of Letters Patent.

Patented Sept. 8, 1908.

Application filed February 13, 1908. Serial No. 415,740.

To all whom it may concern:

Be it known that I, CYRUS L. BUCKWALTER, a citizen of the United States, residing at Loudonville, in the county of Ashland and 5 State of Ohio, have invented certain new and useful Improvements in Audiphones; and I do declare the following to be a full, clear, and exact description of the invention, such as will enable others skilled in the art 10 to which it appertains to make and use the same.

My invention relates to audiphones, dentiphones or the like, and the object of the invention is to materially increase the vibration, and by increasing the tension upon the 15 diaphragm and transmitting the amplified vibrations produced thereby to intensify the action on the mouth bit or piece.

A further object of the invention is to provide a device of this character which may be conveniently transported from place to place and which may also be locked in open position by the supporting handle of the device.

With these and other objects in view, the 25 invention consists of certain novel features of construction, combination and arrangement of parts, as will be more fully described and particularly pointed out in the appended claims.

30 In the drawings: Figure 1 is a side elevation of the device, Fig. 2 is a longitudinal section, Fig. 3 is a transverse section on the line 3—3 of Fig. 2, Fig. 4 is a detail perspective view of the diaphragm, and Fig. 5 is a section 35 perspective view of the clamp and its associated handle.

Referring more especially to the drawings, 1, 2 and 3 represent respectively telescoping sections, which are arranged to collapse so 40 that the device may be carried in the pocket of a deaf person. The section 1 is supplied at its outer end with thickened shell 4, into which is bored the holes 5 for the reception of a plurality of spiral springs 6, upon which 45 the pins 7 of the diaphragm 8 are adapted to rest. These springs are adapted to act in opposition to a spiral spring 9, which is secured at one end to an eye 10 carried upon a headed block 10^a, which passes through the dia- 50 phragm and has a coil spring 10^b surrounding its shank between the diaphragm and the headed end to permit of a resilient connection between the two. The spring 9 is connected at its opposite end to the mouth piece 55 or articulator 11 by an eye 12.

The sections 2 and 3 are held distended in

any suitable spring like manner, but I preferably use a spring latch carried by the section 2 and adapted to engage an aperture in the section 3.

60 The sections 1 and 2 are preferably held apart by a device which is controlled by the handle, which I shall now describe. Secured to the section 1 is a spring 13 having a right angular end 14 passing through an aperture 15, formed in the outer section 1 and adapted to engage an aperture 16, formed upon the inner end of the casing 2. The inherent resiliency of the spring 13 normally holds its angular end 14 out of engagement with the 65 aperture 16, and in order that it may be held in engagement therewith I surround the section 1 with a spring clip 17, which is provided with a pair of ears extending tangentially therefrom to receive the supporting handle 70 18. This handle is eccentrically pivoted to the ears, and is provided with a cam face 19, adapted to pass through an aperture 20, formed in the spring clip so as to engage the upper side of the spring 15 and force its angular extension 14 into engagement with the aperture 16 in the inner section 2. When the handle is lowered the spring retracts its locking end so that the sections are allowed to collapse under the influence of the spring 9. 85

From the foregoing description, taken in connection with the accompanying drawings, the construction and operation of the invention will be readily understood without requiring a more extended explanation. 90

Various changes in the form, proportion and the minor details of construction may be resorted to without departing from the principle or sacrificing any of the advantages of this invention as defined in the appended 95 claims.

What I claim and desire to secure by Letters Patent is:—

1. In an audiphone, a mouth piece, a diaphragm therefor, of a plurality of telescoping 100 sections connecting the same, and an intensifier connected to the diaphragm and mouth piece which comprises a retractile member for the sections.

2. An audiphone comprising a plurality of 105 telescoping sections, a diaphragm secured to one of said sections, a mouth piece secured to another of said sections, an intensifier connected with the diaphragm and the mouth piece which comprises a spiral retractile 110 spring adapted to normally hold the sections collapsed or telescoped, a handle on one of

the sections, and means operated by the handle for holding the sections in extended position.

3. In an audiphone, a roller, a plurality of 5 telescoping sections, a mouth piece carried by one of said sections, a diaphragm carried by another of said sections, means to normally hold said sections in collapsed position, said means acting as an intensifier, a re-
10 silent spring catch carried by one of the sections and adapted to engage its adjoining

sections to hold it in extended position, a spring operating handle carried by the spring clip and adapted to operate the catch.

In testimony whereof I have hereunto set 15 my hand in presence of two subscribing witnesses.

CYRUS L. BUCKWALTER.

Witnesses:

J. W. WHITNEY,
W. R. REED.
